UNITED STATES PATENT OFFICE.

FREDERICK W. WAKEFIELD, OF VERMILION, OHIO, ASSIGNOR TO THE F. W. WAKEFIELD
BRASS COMPANY, OF VERMILION, OHIO, A CORPORATION OF OHIO.

LIGHTING-FIXTURE.

1,168,350.

Specification of Letters Patent.

Patented Jan. 18, 1916.

Application filed April 28, 1912. Serial No. 693,299.

To all whom it may concern:

Be it known that I, FREDERICK W. WAKEFIELD, a citizen of the United States, and a resident of Vermilion, county of Erie, and 5 State of Ohio, have invented a new and useful Improvement in Lighting-Fixtures, of which the following is a specification, the principle of the invention being herein explained and the best mode in which I have 10 contemplated applying that principle, so as to distinguish it from other inventions.

The present invention relates to an insulated coupling, and more particularly to an improved coupling for use in electric 15 lighting connections.

It is particularly adapted to use in connecting an electric lamp to a support upon a wall or ceiling, as the support and the lamp must be entirely and completely insulated 20 from each other.

To the accomplishment of the foregoing and related ends, said invention, then, consists of the means hereinafter fully described and particularly pointed out in the claim.

25 The annexed drawing and the following description set forth in detail certain mechanism embodying the invention, such disclosed means constituting, however, but one of various mechanical forms in which the 30 principle of the invention may be used.

In said annexed drawing:—Figure 1 is a section showing a ceiling and a conduit containing wires which is connected with my improved coupling; Fig. 2 is a similar 35 section showing the coupling when used with a crowfoot or bracket; and Fig. 3 is a vertical central section through the device shown in Fig. 2.

In Fig. 1 there is shown a ceiling 1 in 40 which is mounted a box 2 set into the ceiling and having an aperture 3 at the top in which there may be inserted the end of a conduit 4 adapted to contain insulated wires 5 leading to the source of current. The end 45 of the conduit 4 may be threaded and will be engaged by a socket or connecting member 6 which is apertured and interiorly threaded, and has projecting jaws 7 extending outwardly therefrom. These two jaws 50 7 are attached to a pin 8 which is set in the insulating block 9 and projects beyond the same on either side. A similar connecting or socket member 10 will be attached in like manner about a second pin 20, (see

55 Figs. 2 and 3) which is above the pin 8 and at right angles thereto, such two pins lying in parallel planes which are spaced from each other. It is unimportant as to whether the pin is pivoted in the block 9 or the jaws are pivotally attached to the pin, as either 60 construction will give the universal joint action which is sought. The electrical wires 5 are adapted to extend through the aperture in the socket member 6 and will then pass around the insulating block 9 and 65 through the aperture 11 in the socket member 10.

The conduit 4 is preferably of metal and is generally laid along the ceiling and parallel thereto. It is thus impossible to lead the 70 end through the ceiling except by bending the conduit in a sharp curve. It is, of course, extremely difficult to bend a metal conduit at right angles, or at possibly a little more than right angles, in this case were 75 the conduit to project at right angles to the ceiling, and for this reason the usual connection of this conduit to the electric light bulb is such that the bulb will stand in a position other than vertical. By using a 80 universal joint of the construction here shown it is possible to secure a vertical position for the electric bulb without bending the conduit 4 except at the very gentle curve 85 illustrated in Fig. 1, which is readily possible without straining the conduit.

The present coupling is designed for use not only with flexible metal conduits, but also with rigid brackets such as a crowfoot 90 12 (see Fig. 2) which will be attached directly to the ceiling. The wires 5 will then project through an aperture in the base 13 of the crowfoot, and will pass through an aperture 14 in the projecting portion of the same. This aperture 14 will be threaded 95 and adapted to engage a socket member 6 similar to the one shown in Fig. 1, except that it is of less exterior diameter and is exteriorly threaded to engage the threaded aperture in the crowfoot. In all other respects the coupling shown in Fig. 2 is identical 100 with that shown in Fig. 1.

In Fig. 3 the position of the pins is shown, and it will be noticed that they are spaced a considerable distance apart in the block 9, 105 thus completely insulating the electrical bulb from the ceiling or wall through the coupling. The only electrical connection

between the wall and the bulb will be the wires 5 which are, of course, insulated from the conduit 4, or from the crowfoot 12, when used with such a member.

5 The simplicity of construction and ease of connection render my improved coupling of great advantage in electrical wiring of various types, while the appearance of the coupling is such as to adapt it to use with 10 various ornamental fixtures without in any way injuring the effect intended to be produced.

Other modes of applying the principle of my invention may be employed instead 15 of the one explained, change being made as regards the mechanism herein disclosed, provided the means stated by the following claim or the equivalent of such stated means be employed.

Copies of this patent may be obtained for five cents each, by addressing the "Commissioner of Patents, Washington, D. C."

I therefore particularly point out and distinctly claim as my invention:—

The combination of an outlet box having an aperture in the top thereof, a cable-containing conduit passing through such aperture in said box, and an insulated universal joint formed of upper and lower portions connected through insulating material and constructed to allow the convenient passage of the electrical cables, having its upper portion directly connected to said conduit, and allowing the vertical disposition of the lower portion and its complete insulation from said conduit and said box.

Signed by me this 23d day of April, 1912.

FREDERICK W. WAKEFIELD.
